UNITED STATES PATENT OFFICE.

FREDERICK W. COLE, OF NEWTON, MASSACHUSETTS, ASSIGNOR, BY MESNE ASSIGNMENTS, TO THE UNITED STATES FIRE AND POLICE TELEGRAPH COMPANY, OF PORTLAND, MAINE, AND BOSTON, MASSACHUSETTS.

NON-INTERFERENCE SIGNAL-BOX.

SPECIFICATION forming part of Letters Patent No. 553,839, dated February 4, 1896.

Application filed March 7, 1891. Serial No. 384,072. (No model.)

To all whom it may concern:

Be it known that I, FREDERICK W. COLE, of Newton, county of Middlesex, State of Massachusetts, have invented an Improvement 5 in Non-Interference Signal-Boxes, of which the following description, in connection with the accompanying drawings, is a specification, like letters and figures on the drawings representing like parts.

10 This invention has for its object to improve the construction of signal-boxes, being especially applicable to that class of signal-boxes known as "successive non-interference boxes."

15 The invention consists in the combination, with signaling mechanism, a non-interference magnet and its armature adapted to move out of its magnetic field, of signal-controlling and retaining mechanism operated to retain a set 20 signal by the said armature when moved out of its magnetic field and to release said retained signal when said armature is restored; also in the combination, with signaling mechanism, a non-interference magnet and its armature adapted to move out of its magnetic field, of signal controlling and retaining mechanism operated to retain a set signal by the 25 said armature when moved out of its magnetic field and to release said retained signal 30 when said armature is restored, and timing mechanism holding the signal-circuit closed a longer time than the longest closure in any signal before giving the control of the line to the signal-wheel; also in the combination, 35 with signaling mechanism, a non-interference magnet and its armature adapted to move out of its magnetic field or field of force, of a signal-controller governed by said armature, and means controlled by the train in running 40 for holding the signaling-key with its circuit contacts closed during one round of the signal-wheel at each operation of the box; also in the combination, with signaling mechanism, a non-interference magnet and its armature, of a signal-controller governed by said armature, and a stopping device for the train, one of the co-operating members of which is 45 governed by the said armature, and a restoring device operated by the train in running 50 for restoring said armature; also in the com-

bination, with a signaling-train, of a stopping device consisting of two members, one of which is controlled by the non-interference magnet and the other by a hand-operated pull or equivalent signaling-lever; also in the combination of parts which, by their co-operation, enable the signaling-train to be wound at each operation of the pull or signaling lever more than sufficient for the operation of the signaling-train in the transmission of one 60 complete signal, whereby a force may be accumulated; also in many details of construction to be hereinafter pointed out.

Figure 1 shows in side view a successive non-interference signal-box embodying this 65 invention, the pull being omitted; Fig. 2, a plan view of the signal-box shown in Fig. 1, the non-interference magnet and a portion of the frame being omitted; and Figs. 3 and 4, sectional details to be referred to.

The signaling mechanism herein shown consists of a toothed wheel a_1 , loosely mounted on a shaft a_2 and engaging a pinion a_3 , secured to a shaft a_4 , which carries a toothed wheel a_5 , engaging a pinion a_6 , secured to a shaft a_7 , carrying a toothed wheel a_8 , which engages a pinion a_9 , secured to a shaft a_{10} , carrying an escape-wheel a_{11} , which is engaged by a suitable pallet a_{12} . The signal-wheel a_{13} is placed on the shaft a_7 , with which co-operates a signaling-key a_{14} , pivoted at a_{15} and carrying one of the circuit making and breaking contacts 70 2. A block a_{16} is secured to the framework, which supports a yielding pin or arm a_{17} , carrying the other circuit making and breaking 75 contacts 3.

The non-interference magnet b is supported by the framework, its armature b' being carried by a lever b^2 , pivoted at b^3 to the framework, said lever being extended, as at b^4 , and 80 carrying a pen b^5 .

A locking-bar b^6 , sleeved on the shaft a_4 and lying diametrically across the toothed wheel a_5 , has at each end a locking projection, as b^7 , said projections extending through holes 95 in the said toothed wheel a_5 , and said bar is pressed into its forward position, as represented in Figs. 2 and 4, by a spring b^8 .

When the armature is attracted, the outer end of the lever b^4 will lie in the path of move- 100

ment of the pins b^7 to engage one or the other of them and thereby stop the train, such members constituting the stopping device for the train.

- 5 The sleeve b^9 of the bar b^6 has on it two projections b^{10} b^{10} , extending in opposite directions and at right angles with relation to the bar b^6 . The faces of each projection are beveled or inclined, and on the shaft a' a disk b^{12} 10 is fastened which has several beveled-faced projections b^{13} on its periphery, one or another of which will engage one of the projections b^{10} , and as the beveled faces act one upon the other the bar b^6 will be moved rearwardly 15 against the tension of the spring b^8 and will thereby withdraw its projections or pins b^7 from engagement with the lever b^4 to release the train when the disk is revolved.
- The disk b^{12} forms part of a barrel b^{14} , which 20 receives the main spring, one end of which is attached to said barrel and the other end to the hub c on the toothed wheel a . The barrel b^{14} is fixed on the shaft a' , and the toothed wheel a is mounted loosely on the said shaft.
- 25 A pawl c' is pivoted to the disk b^{12} , and is held pressed into engagement with a ratchet-toothed wheel c^2 by a spring c^3 . The ratchet-toothed wheel c^2 is held in fixed position by pins or studs c^4 , secured to the framework.
- 30 The ratchet-toothed wheel c^5 (shown in dotted lines, Fig. 1, and full lines, Figs. 2 and 3) is also fixed to the shaft a' , and the winding arm or pull c^6 is pivoted to the door of the box or face-plate c^7 , which carries a spring-pressed 35 pawl c^8 , which engages the said ratchet-toothed wheel. As the pull c^6 is depressed, the ratchet-wheel c^5 will be rotated a distance equal to one or more teeth, the shaft a' correspondingly rotating the disk b^{12} so that one of 40 its pins or projections b^{13} engages one of the projections b^{10} and moves the bar b^6 longitudinally on the shaft a' to thereby release the train. By this means it will be seen that the main spring may be wound and the train released, and the parts are so proportioned that 45 the main spring may be wound at each operation of the pull c^6 enough for several signals, on which account said pull will be known as an "accumulative pull" or "winding device."

There is arranged on the wheel a a flange c^{10} , which engages a projection c^{12} on the spring-pressed pawl c' when the disk has been moved a certain distance independently of the 55 toothed wheel a —as, for instance, when the spring has been completely wound—and when so engaging the pawl c' holds said pawl and prevents it from entering the next tooth of the ratchet-wheel c^2 . A stopping device c^{13} is 60 also arranged on the barrel b^{14} , which acts as a stop for the wheel a , it being in the path of the flange c^{10} as the spring runs down. This winding mechanism may be applied to any other form of signaling mechanism than that 65 herein shown.

An arm d extends from the circuit-changing lever a^{14} having a shouldered end d' , with

which the pin b^5 on the arm b^4 of the armature-carrying lever co-operates.

The signal-wheel herein shown is made to 70 maintain the signaling-circuit closed all the time except during short intervals for the signal impulses—that is to say, during the intervals of time between the several groups of numbers on the signal-wheel the signaling- 75 circuit will be closed, and said wheel is herein shown as having on it one round, although a wheel having several rounds on it may be employed.

When the signaling-train is let off or operated and the armature remains attracted, as represented in Fig. 1, the signal will be transmitted without interruption, the pin b^5 occupying a fixed position in a recess or space just above the shoulder d' of the arm d at the time 85 the circuit is open at the home box, so as to mechanically hold the armature in its attracted position when the magnet is demagnetized.

The "home box" is intended to mean that 90 box which is being operated, in contradistinction to the other boxes in the circuit. If the signaling-circuit is opened during the time the circuit is closed at the home box, the armature will be retracted and the pin b^5 will pass 95 down over the shoulder d' of the arm d to thereby mechanically hold the circuit-changing lever a^{14} from operating. The retractile spring is designed to move the armature b' 100 out of the magnetic field when the magnet is demagnetized and the armature released, and when so moved it will there remain until positively restored, and during such time the signaling-circuit will be kept closed at the 105 home box, although the signaling-train and signal-wheel may be operated.

The lever b^2 carrying the armature has a projection b^{20} , (see dotted lines, Fig. 1,) and pins 4 are placed on the toothed wheel a' , two such pins being herein shown, located substantially diametrically opposite each other, one or the other of which will strike the said projection b^{20} and restore the armature to its attracted position immediately after the locking-pin b^7 has passed by the outer or engaging end of the arm b^4 . These pins are arranged to restore the armature prior to the beginning 110 of a round of the signal, and as it is very important that the armature should be restored and the line under the influence of the non-interference magnet only for a longer time than the longest closure in any signal, and as the closures in the signaling-circuit by the signal-wheel herein shown are exceedingly 115 long, I have provided means for accomplishing this result, which herein consists of short arms or holders $e e$, fixed to the shaft a^3 , one or the other of which will engage a projection e' of the circuit-changing lever a^{14} and hold the said lever against vibration and with the 120 circuit-contacts closed such a length of time.

In lieu of the holders $e e$, which operate mechanically to hold the circuit-changing lever or signaling-key, said holders may close 125

a shunt for the signal-wheel or otherwise prevent the signal being transmitted, and at the same time keep the non-interference magnet in circuit. As herein shown, the arm *e* will hold the lever *a*¹⁴ during a complete round of the signal-wheel *a*¹³, and it is during this time that the pin 4 operates to restore the armature *b*'.

While I do not desire to limit my invention to this particular means for holding the circuit-lever from vibrating this predetermined length of time, similar means controlled by the train in running may be employed.

If, when the box is pulled, the line is found to be opened, as by the transmission of a signal from a distant box, the armature will immediately retract and moves out of the magnetic field, but is immediately restored by the pin 4, and as said pin passes by the short arm *b*²⁰ the armature will again retract if the line continues to remain open, and moves out of the magnetic field, where it remains, holding the circuit-lever *a*¹⁴ from vibrating, and with the circuit-contacts closed by means of the arm *b*⁴. The parts will remain in this condition until the opposite pin 4 on the wheel *a*⁴ arrives in position to engage the short arm *b*²⁰ and restore the armature; and when said pin 4 arrives in position to accomplish such result the arm or holder *e* also arrives in position to again hold the arm *a*¹⁴ with the circuit-contacts 2 3 closed, independent of the arm *b*⁴. The time consumed by the train in running after the said pin 4 has restored the armature, and before the beginning of the next succeeding round is longer than the longest closure in any signal, and if the armature remains attracted during this length of time the signal can then be transmitted. It is during this time that the arm *e* acts to hold the arm *a*¹⁴, and to keep the circuit-contacts 2 3 closed. The arm *e*, however, passes by the lug or projection *e*' just before the beginning of the next succeeding round. This arm *b*⁴ carried or moved by the armature adapted to be moved out of its magnetic field, and the arm *d*, having the shouleder end portion *d*' co-operating with the pin *b*⁵ on the arm *b*⁴, herein constitute the signal controlling and retaining mechanism; but I do not desire to limit my invention to the particular form of signal controlling and retaining mechanism herein shown, as it is obvious that it may be changed and yet come within the spirit and scope of this invention; also this group of elements may be made to simply cut out or render inoperative the signaling mechanism, in which instance said mechanism will operate only as a signal-controller, and the arm *b*⁴ will constitute the essential element.

I do not desire to limit my invention to its application to a signaling mechanism having a circuit-changing lever with contacts, as 2 3, and a signal-wheel for operating the said lever, as it is obvious that any other well-known or suitable form of box-number cir-

cuit-changing device may be employed, and furthermore I do not desire to limit my invention to the application of signaling mechanism wherein the aforesaid circuit-changing lever is held positively from vibrating, as the signal-wheel may be otherwise prevented from transmitting its signal.

I claim—

1. In a non-interference signal-box, a signaling mechanism, a non-interference magnet and its armature adapted to move out of the field of force, a signal-controller governed by said armature, and a stopping device for the train, one of the co-operating members of which is governed by the said armature, and a restoring device operated by the train in running for restoring the said armature substantially as described.

2. In a non-interference signal-box, signaling mechanism, a non-interference magnet and its armature adapted to move out of the field of force, a signal-controller governed by said armature, and a stopping device for the train, one of the co-operating members of which is governed by the said armature, and a restoring device operated by the train in running for restoring the said armature, and means controlled by the train in running for holding the signaling-circuit closed for a longer time than the longest closure in any signal just before giving the control of the said circuit to the signal-wheel substantially as described.

3. In a successive non-interference signal-box, signaling mechanism, a non-interference magnet and its armature adapted to move out of its magnetic field, combined with signal controlling and retaining mechanism for retaining and thereafter permitting the transmission of the set signal, said signal-retaining device being adapted to retain the set signal by the retracting-armature, and to permit the transmission of the retained signal when in its attracted position, and a restoring device operated by the train in running for restoring said retracted armature, substantially as described.

4. In a successive non-interference signal-box, signaling mechanism, a non-interference magnet and its armature adapted to move out of its magnetic field, combined with signal controlling and retaining mechanism for retaining and thereafter releasing the set signal, said mechanism being operated to retain the set signal by the retracting-armature, and to release it when said armature is in its attracted position, and a restoring device operated by the train in running for restoring said retracted armature, and means controlled by the train in running for holding the signaling-circuit closed for a longer time than the longest closure in any signal just before the beginning of a succeeding round, substantially as described.

5. In a successive non-interference signal-box, signaling mechanism, a non-interference magnet and its armature adapted to move

out of its magnetic field, combined with signal controlling and retaining mechanism, operated to retain a set signal by the said armature when moved out of its magnetic field, 5 and to release said retained signal when said armature is restored, substantially as described.

6. In a non-interference signal-box, a signaling-train combined with a stopping device 10 consisting of two members one of which is controlled by the non-interference magnet, and the other by a hand-operated pull, substantially as described.

7. In a signal-box, a signaling-train combined with a winding mechanism therefor, consisting of a barrel and toothed driving-wheel, a main spring connected at one end to the barrel and at the other end to the wheel, a fixed ratchet-wheel, a pawl carried by said 15 barrel, and means for rotating said barrel to wind the spring and a stop projection, as c^{13} , on the barrel, which engages the stop projection, as c^{10} , on the driving-wheel, substantially as described.

25 8. In a non-interference signal-box, signaling mechanism, a non-interference magnet and its armature, a signal-controller governed by said armature, a bar as b^6 carried by one of the moving parts of the train having a pin 30 engaged by said signal-controller, means for moving the said bar to disengage it from the signal-controller and release the train substantially as described.

9. In a signal-box, a signaling-train, combined with a winding mechanism therefor, consisting of a barrel and toothed driving-wheel, a main spring connected at one end to the barrel and at the other end to the wheel, a ratchet-wheel, a pawl carried by said 35 barrel, a cam projection carried by the toothed wheel, which co-operates with said pawl when the spring is wound up substantially as described.

40 10. In a signal-box, a signaling-train, combined with a stopping device comprising an independently-movable member carried by one of the moving parts of the train and a co-operating member, and a hand-operated pull for moving said independently-movable member 45 into and out of co-operation with the said co-operating member substantially as described.

50 11. In a non-interference signal-box, signaling mechanism having a signal-wheel and signal-key, a non-interference magnet and its armature, a signal-controller governed by said armature, and means controlled by the train in running which holds the signal-key with its circuit-contacts closed for a predetermined 55 length of time just before the beginning of a round of the box-number, during which time the signal-controller is free to act to mechanically lock the signal-key with its circuit-contacts closed, substantially as described.

60 65 12. In a signal-box, a signal-train, a non-interference magnet and its armature, combined with a signal-key having two parts or

portions, one of which is governed by the signal-wheel and the other by the train in running, said train co-operating with said key to 70 prevent its co-operation with the signal-wheel, and also to maintain the circuit closed for a predetermined length of time just before the beginning of a round of the box-number, substantially as described.

75 13. In a non-interference signal-box, signaling mechanism comprising a signal-wheel and signaling-key, a non-interference magnet and its armature, and a signal-controller governed by said armature, and also by two 80 members of the train in running, one of which members, as the signal-wheel, allows said signal-controller freedom of action on closures of the circuit during the transmission of the signal, and the other, as the holder 85 e , allows said signal-controller freedom of action for an interval of time longer than the longest closure in any signal, after the pull has been operated and before the transmission of the first impulse of the signal, substantially as described.

90 14. In a successive non-interference signal-box, signaling mechanism, a non-interference magnet and its armature adapted to move out of its magnetic field, combined with signal controlling and retaining mechanism, operated to retain a set signal by the said armature when moved out of its magnetic field, and to release said retained signal when 95 said armature is restored; timing mechanism 100 for holding the signaling-circuit closed a longer time than the longest closure in any signal before giving the control of the line to the signal-wheel, substantially as described.

105 15. In a non-interference signal-box, a signal-train, a non-interference magnet and its armature, combined with a stopping device for the train, one member of which operates to hold the said armature in its attracted position, substantially as described.

16. In a signal-box, a train, a main actuating-spring therefor, a driving-wheel for the train connected with one end of said spring, a winding-disk connected with the other end 115 of said spring, a locking lever or stop for the train, a pull for simultaneously winding the spring and releasing the locking-lever to set the train in condition to transmit its signal, a pawl and ratchet for holding the winding-disk against backward rotation, and a disengaging device for said pawl which prevents overwinding of the spring, but does not interfere with the action of the pull, substantially as described.

120 17. In a signal-box, a signaling-train, a main actuating-spring therefor, a stop for the train, and operating device for winding the spring and setting the signaling-train in condition to transmit its signal, a pawl and 125 ratchet for preventing the backward action of the spring, and a disengaging device for said pawl, operating when the spring is wound up, substantially as described.

18. In a signal-box, a signaling-train, and stop therefor, a main actuating-spring for said train connected at one end with the driving-wheel of the train, and at the other end with a winding device, a hand-lever for turning said winding device and also for setting the signaling-train in condition to transmit its signal, a pawl and ratchet to prevent backward action of said spring, and a disengaging device for said pawl operating when the spring is wound up, to prevent overwinding of the spring without interfering with the action of the hand-lever, substantially as described. 35
19. In a signal-box, a signaling-train, and stop therefor, a main actuating-spring for said train connected at one end with the driving-wheel of the train, and at the other end with a winding device, a hand-lever for turning said winding device and also for setting the 40 signaling-train in condition to transmit its signal, a pawl and ratchet to prevent backward action of said spring, and a disengaging device for said pawl carried by said driving-wheel. 45
20. In a non-interference signal-box, a signaling-train, a main actuating-spring therefor, a locking-lever for said train governed by the armature of the non-interference magnet, a hand-operated pull for setting the signaling- 50 train in condition to transmit its signal, a connection between said pull and the main spring whereby the spring may be wound by said pull when operated, and a disengaging device which prevents overwinding of the spring without interfering with the operation of the pull, substantially as described. 55
21. In a signal-box, the combination of a signaling-train, a signal-key, a non-interference magnet, and its armature, which whenever retracted mechanically locks the signal-key with its circuit-contacts closed, substantially as described. 60
22. In a signal-box, the combination of a signaling-train, a signal-key, a non-interference magnet, and its armature, which whenever retracted mechanically locks the signal-key with its circuit-contacts closed, and said key whenever operated to open the circuit mechanically locks the armature in its attracted position, substantially as described. 65
23. In a non-interference signal-box, a signaling mechanism having a signal-wheel, a signal-key, a non-interference magnet and its armature, a signal-controller governed by said armature, which is free to retract on closures 70 of the circuit at the home box, and whenever it retracts locks the signal-key with its circuit-contacts closed, substantially as described. 75
